UNITED STATES PATENT OFFICE.

WILHELMINE ANDERSON, OF WEST NEW YORK, NEW JERSEY.

CONVERTIBLE TRUNK.

1,374,346.

Specification of Letters Patent. Patented Apr. 12, 1921.

Application filed September 2, 1919. Serial No. 321,132.

To all whom it may concern:

Be it known that I, WILHELMINE ANDERSON, a citizen of Sweden, residing in the city of West New York, in Hudson county, 5 in the State of New Jersey, have invented certain new and useful Improvements in Convertible Trunks, of which the following is a specification.

This invention relates to that class of 10 trunks having hinged trunk sections which are constructed and operatively connected in such a manner as to form a useful article of furniture, such as a wardrobe or desk, when not in use for the usual and ordinary 15 purposes of a trunk.

The principal object of the invention is to provide a simple, economical and efficient convertible trunk, adapted to be converted with facility in such a manner as to enable 20 it to be employed as a useful article of household furniture, such as a wardrobe or desk, or an improved combined trunk, wardrobe and desk.

Other and further objects of the invention 25 will appear from the following description and claims, and from an inspection of the accompanying drawings, which are made a part hereof.

The invention consists in the features, 30 combinations, details of construction and arrangement of parts herein described and claimed.

In the accompanying drawings, Figure 1 is a perspective view of an improved 35 convertible trunk constructed in accordance with my invention, showing the trunk closed, in full lines, and with one of the hinged trunk sections raised or in open position, in broken lines;

Fig. 2, is a side view in perspective of a 40 trunk, such as that shown in Fig. 1, with the parts arranged in position to form a wardrobe having a drawer-containing section located in front of a wardrobe compartment, the wardrobe compartment being 45 of greater height than the drawer section and extending down back of the latter, but in position to be readily accessible;

Fig. 3, is a view in central vertical section 50 taken on line 3 of Fig. 2, looking in the direction indicated by the arrows;

Fig. 4, is a detail view in perspective of 55 the wardrobe section, showing the same provided with a bottom opening adapted to permit garments hung in the section to extend downward through the open bottom,

and showing a telescoping inner member, in a partially lowered position with respect to the outer wardrobe member;

Fig. 5, is a detail view in perspective, of 60 the drawer-containing compartment or section shown in Figs. 1, 2 and 3;

Fig. 6, is a view in perspective of the trunk shown in Fig. 1, with the trunk sections and parts in position to form a flat- 65 topped desk;

Fig. 7, is a view in perspective of a combined wardrobe and desk formed by placing 70 a wardrobe section directly over the drawer-containing section, with the hinged connecting member or table member in horizontal position between said upper and lower sections—the wardrobe section being a modification of the wardrobe section shown in 75 Figs. 1, 2, 3, and 4, in that it has a fixed bottom, and fixed rigidly connected walls on all sides except the front side, which has suitable hinged doors;

Fig. 8 is a detail view in perspective, of 80 the telescoping inner member of the wardrobe section, shown in Figs. 2, 3 and 4;

Fig. 9 is an enlarged detail view of the hinge connections; and

Fig. 10 is a detail view in section on line 85 10 of Fig. 9.

In constructing an improved convertible trunk in accordance with my invention, I provide a wardrobe section 1, a drawer-containing section 2, and a flat outer back or connecting member 3, the section 2 being 90 hinged to what is normally the lower margin of the connecting member 3 by means of suitable hinges 4, and the upper or wardrobe section 1 being connected with the upper margin of the connecting member or 95 main desk-top forming member 3 by means of suitable hinges 5. The back or desk-top forming and connecting member 3 is, by preference flat, and of suitable dimensions to form the main outer back wall portion of 100 the trunk, and is adapted to cover and inclose the rear sides of both of the upper or wardrobe section 1 and the lower or drawer-containing section 2, and form a strong and rigid outer back wall of the entire trunk 105 when closed.

The drawer-containing section 2 has end walls 6 and 7, a front side wall 8 and a rear side wall 9, and bottom wall 10, all rigidly connected, and firmly secured together and braced by suitable connecting means including metallic marginal connect-

ing and guarding strips 11 which cover all of the margins of said trunk-section 2 that are exposed when the trunk is in use or closed. The other main trunk section or wardrobe section 1, when constructed as shown in Figs. 1, 2, 3 and 4, comprises in its construction end walls 12 and 13, a top wall 14, and front side wall 15 all rigidly connected at their outer margins by means 10 of metallic connecting and guarding strips or angle iron members, or other suitable connecting and guarding means. And the rear inner side wall of said section 1 is, by preference, provided with a suitable 15 opening 17 adapted to permit garments to extend downward therethrough when said section is in raised or wardrobe-forming position, as shown in Figs. 2, 3, and 4, and has or may consist of a hinged wall or door 20 18 provided with marginal inclosing flanges 19, 19, and 21, hinged to the outer margin of said trunk section 1 and adapted to form a closure for said opening 17. The door or inner back wall 18 is provided with a 25 strip or hinge portion 22 of heavy canvas, leather or other suitable flexible material adapted to form a water-proof closure across the adjacent marginal or hinged edge of said door and the edge of the section 1 to 30 which the door is flexibly connected by means of such flexible connection or hinge 22. The outer surfaces of the walls of the upper trunk section 1, the lower trunk section 2, and the desk-top forming connecting member 3 are, by preference, all covered with a suitable protecting layer 23 of canvas, leather or sheet metal, or other well-known form of strong water-proof sheet material, the main body portions of 35 the walls of the trunk sections being made of wood, fiber board, composition or other suitable material adapted to provide the desired rigidity and strength without unnecessary weight.

45 The drawer-containing section is provided with suitable sliding drawers 24, 25 and 26, of suitable dimensions, and which are adapted to be slidably mounted in said section in any suitable ordinary and well 50 known manner, and by preference, in such a manner as to be readily inverted, or removed and replaced in any desired order.

In order to strengthen and enable the open side or bottom of the wardrobe section 55 to be still more tightly and securely closed when desired, and to enable it to be readily opened so as to be suitable for use as a wardrobe member adapted to permit garments hung therein to extend down through the 60 open bottom when said section is in wardrobe-forming position as indicated in Figs. 2 and 3, the inner margin is provided with a strong corner strip or rib 27, and an inner telescoping closure member 28, having up- 65 right corner guides 29 and a closed bot-

tom 30 adapted to fit snugly into and tightly close the opening 17, and to be lowered to the positions shown in Figs. 2 and 3, and raised to closed position so as to be covered and inclosed inside of and 70 by means of the door 18, is provided and slidably mounted in the section 1, in such position that the corner guiding members 29 are adapted to slide in the corresponding corners of said trunk-section 1. 75

The front side of the inner or lower telescoping member 28, which is on the open side of the upper or wardrobe section 1, is open, and the same is true of the opposite or rear side, but a low front side wall 31 and 80 low rear side wall 32, and suitable end walls 33, are provided and joined together tightly at their margins, so as to form a tight closure for the bottom of the trunk section 1, when the inner telescoping member 28 is in 85 raised or closed position. The ends of the said telescoping member 28 may be closed entirely or to any desired extent by means of thin end walls 34, 34, which may be of any desired height, even to the extent of reaching from the bottom of the upper or wardrobe section 1, to the bottom of the drawer section 2 when the parts are in position to be used as a wardrobe, as shown in Figs. 2 and 3. (See also Figs. 4 and 8.) The end wall 90 plates 34, 34 may be omitted, however, when desired, in order to permit any desired form of garment supports to be mounted in position in the wardrobe section. The garment-supports shown in the drawings are of a 95 very simple form consisting of bars or shelf-supports 35 hinged to supporting brackets 36 mounted in any suitable manner on a suitable support, such as the wall 14 of the wardrobe section 1, so that the swinging 100 ends of the rods may be swung back to said wall and forward in the direction of the front or open side of the wardrobe section, as shown in Figs. 3 and 4; and suitable adjustable rods or garment-supports 37 are 110 adjustably and removably mounted upon these hinged rods or shelf supports. It is obvious that any desired number of pairs of the rods or shelf-supports 35 may be adjustably and removably mounted in the 115 wardrobe section 1 in position to support garment-supporting rods 36 or shelves for containing books or other articles, as desired, or that any desired suitable form of inner fixtures may be employed in either 120 of the trunk sections 1 and 2. The open side of the wardrobe section 1 is provided with one or more swinging doors 38 hinged to the front margins of said section. And the usual metallic flange or projecting marginal strip 39 is fixed to and extends along the three outer edges of the wardrobe section 1 in position to overlap the corresponding edges of the opposite trunk section 2, when the trunk is closed. 125 130

The inner telescoping member 28 is provided with short foldable feet or bosses 40 adapted to rest upon the floor level and support the forward bottom edge of the said 5 telescoping member; and supporting pins or catches 41 at the upper edge of the lower or inner telescoping member 28 are adapted to engage the lower extremity of the trunk section 1, so as to support the forward portion 10 of the latter in raised position when the parts are in position to form a wardrobe, as shown in Figs. 2 and 3. These catches may be in the form of mere pins removably inserted in suitable openings in either the 15 inner telescoping section 28 or the wardrobe section 1, and adapted to engage an edge or notch in the adjacent part of the other one of said telescoping parts.

The door 18 at the back lower margin of 20 the trunk section 1 is provided at each end with a foldable flap 42 having one of its edges secured in water tight engagement with the lower edge of the corresponding side wall of the section 1 throughout the 25 entire length of said edge, and the other edge of said flap in water tight engagement with the door 18 just inside of the flange 19 but in position to permit the foldable flaps to fold inward on the inside of the adjacent 30 flanges 19 and door 18. The flange 21 on the long edge of the door 18 is flexibly connected with the latter by means of suitable flexible material such as strong canvas or leather, so as to form a water-tight connection with 35 said door; and suitable connecting means, such as a series of headed bolts 43 inserted in suitable openings in the flanges of the door 18 and in openings in the adjacent marginal portions of the wardrobe section 40 1, serve to securely fasten the door in closed water-tight position, when the trunk is to be used as a trunk as distinguished from a wardrobe or desk. Any ordinary and well known form of securing means for holding 45 the door closed and adapted to permit it to be readily opened and tightly closed may be employed.

In Fig. 7 is shown a trunk section 44 which is constructed in all respects the 50 same as the wardrobe section 1 already described and shown in Figs. 1, 2, 3, 4, and 6, except that said section 44 has a fixed rigid wall 45 which is without any opening to permit the garments to hang down at 55 full length therethrough. And, when the form of wardrobe section shown in Fig. 7 and indicated by the numeral 44 is used, the door 18 may be dispensed with; or, as shown in said figure, said door may be 60 turned back to the position in which it is shown in full lines, but partly broken away, and a curtain 46 may be attached in any suitable manner to said door so as to hang down around the back and side margins of 65 the door back of the sections 44 and 2, to

form a curtained compartment, as shown in said figure. In Fig. 7 the wardrobe section 44 is placed directly over or in superposed relation to the section 2, and the main desk-top member 3, which serves 70 to connect the sections 44 and 2, or the sections 1 and 2, as the case may be, by being hinged to each while the device is adjusted for use as a trunk as in Fig. 1, or as a desk as in Fig. 6, is disconnected at 75 its hinges from the wardrobe section 44 and adjusted into position to extend forward between the wardrobe section and the drawer section 2, to form a desk in front of said sections, as shown in Fig. 7. Section 1 may be employed in the same position or in lieu of section 44 as shown in 80 said Fig. 7, if desired. And it is plain that the main desk-top and connecting member 85 3, when connected with both of the sections 1 and 2, by means of the hinges 5, is adapted to enable said sections 1 and 2 to be adjusted to the positions in which they are shown in full lines in Fig. 6, to form a flat-topped desk, without disconnecting 90 any of the hinges, and that the sections 1 and 2 are adapted to be adjusted from the position in which they are shown in full lines in Fig. 6, or desk-forming position, to trunk-forming position, in which they 95 are shown in broken lines in Fig. 6 and in full lines in Fig. 1, without disconnecting the desk-top member 3 from either of the sections 1 or 2.

In order to enable the sections 1 and 2, 100 and other parts to be arranged and used as illustrated in Figs. 2 and 3, it is only necessary to disconnect the desk-top member 3 from the drawer section 2, and leave it connected with the wardrobe section 1, so as 105 to form a support for the latter, and a closure for the bottom portion of the wardrobe compartment the side walls and bottom of which are formed by the telescoping section 28, and the drawer section 2, which also serves to support the forward part of 110 the section 1, when the parts are in the position shown in said Figs. 2 and 3.

In view of the foregoing it will be readily seen that it is highly desirable that 115 means be provided for enabling the connecting desk-top member 3 to be readily connected with and disconnected from either or both of the sections 1 and 2, as desired, and in such a manner that they cannot be disconnected in any way which will enable 120 the trunk to be opened without a key, or without first unlocking and turning the main trunk sections to trunk-opening position.

In order to enable this to be accomplished 125 in a simple and efficient manner, each of the hinges 4 and 5 is provided with a removable pintle 47 in the form of a headed pin or rod having a laterally projecting boss 48 adapted to pass through radial 130

notches 49 in the eye members 49', 49' of the hinges, when the latter are in a desired predetermined position with respect to each other, with the trunk sections 1 and 2 unlocked and in open position. But the radial notches or slots 49 are so disposed that they are out of alinement with each other when the hinge parts are in the position which they occupy when the trunk is closed, thus preventing the removal of either of the pintles while the trunk is closed, but permitting them to be readily removed by first unlocking the trunk and turning the hinged trunk sections 1 and 2, or either of said sections which is to be detached from the part 3, to the required open position to bring the slots 49 into alinement, in which position they are adapted to permit the withdrawal of the pintle 47 by turning the same into position to cause the locking boss 48 to pass out through the slots 49 along with the removable self-locking pintle thus provided. The hinges 5 are thus self-locking, and adapted to prevent the trunk from being opened by removing the pintles or disconnecting the hinges without first unlocking the lock 50, which may be of any desired ordinary and well known or suitable form of trunk lock. The leaves 51 and 52 of the hinges 5 may be made long enough to extend along the margin of the trunk section or connected part to which they are attached throughout the entire length of such margin or edge, and may be integral with or connected with the hinge eyes or sockets at the opposite extremities of the margins or parts connected by means of the hinges, thus affording great strength and forming strong corner-shielding members for the connected marginal portions of the trunk.

In Figs. 9 and 10, the eyes 49' of the two hinge members of a hinge 5—the hinges 4 and 5 being, by preference of identical construction—and the removable pintle 47 and securing or locking boss 48 are shown in full lines in position to prevent the removal of the detachable pintle, or as they would be with the main trunk sections 1 and 2 and outer back wall member 3 in trunk-closing position the boss 48 being seated in a notch 48' in the margin of the back wall member 3, and in such position that the notches 49 in the hinge members 49' are in position to prevent the removal of the boss 48 therethrough until the notches are turned to the position in which they are shown in broken lines in said Figs. 9 and 10, which is the position they are adapted to occupy when the pintle is inserted and the trunk sections and rear back wall member are in trunk-opening position.

Hinge eyes 5' may be secured to the inner back wall member or lid 18 of the trunk section 1 and in position to be pivoted on

the detachable pintles 47 just inside of the eye members 49' of the hinges which connect the outer back wall member with the main trunk sections 1 and 2, if desired, as indicated in Figs. 6 and 10; and the same is true of the hinge member 5' with respect to being connected with and forming hinge connections for the lid or door 9 of the trunk section 2. (See Figs. 5 and 6 and 10.)

I claim:

1. A trunk comprising in its construction a pair of opposite main trunk sections each having a front wall, end walls, and an inner back wall portion the margins of which are movable into and out of trunk-closing engagement with the adjacent corresponding margins of the opposite main trunk section, and a hinged outer connecting back wall member connected with said main trunk sections and acting to overlap, engage and inclose said adjacent margins of the inner back wall portions of said main trunk sections and to hold the rear portions of the main trunk sections in trunk-closing engagement with each other and permit the movement of the same into and out of trunk-closing position.

2. A trunk comprising in its construction a pair of opposite main trunk sections each having a front wall, end walls, and a hinged inner back wall adapted to form a section cover, and a hinged outer connecting back member connected at its opposite edges with the hinged margins of said hinged inner back wall members and the corresponding adjacent hinged margins of said main trunk sections, and acting to overlap, engage and inclose and hold the opposite margins of the main trunk sections and hinged inner back wall members in engagement with each other in trunk-closing position.

3. A convertible trunk comprising in its construction a pair of opposite main trunk sections each having a front wall, end walls, and a hinged inner back wall adapted to form a section cover, a hinged outer connecting back member having hinged connection at its opposite edges with the hinged margins of said hinged inner back wall members and the corresponding adjacent hinged margins of said main trunk sections, and acting to overlap, engage and hold the opposite swinging margins of the main trunk sections and hinged inner wall members in engagement with each other in trunk-closing position, and means for securing the forward portions of said main trunk sections in trunk-closing position.

4. A trunk comprising in its construction a pair of opposite main trunk sections each having a front wall, end walls and a hinged inner back wall the margins of which are movable toward and from the corresponding marginal portions of the opposite main trunk section into and out of trunk-closing

- engagement with each other, an outer connecting back wall member mounted in position to overlap and inclose the adjacent margins of said inner back walls of said 5 main trunk sections, detachable hinge mechanism connected with a marginal portion of said outer connecting back wall member and with the adjacent main trunk section and the hinged margin of the inner back 10 wall of said section and forming a detachable connection between said parts, detachable hinge mechanism connected with the opposite margin of said outer connecting back wall member and with the other one 15 of said main trunk sections and the hinged margin of the inner back wall of said section and forming a detachable connection between said parts, and means for securing the forward portions of said main trunk 20 sections in trunk-closing position.
5. In a trunk of the class described, the combination of a pair of opposite main trunk sections each having a front wall, end walls and an inner back wall portion the 25 margins of which are movable toward and from the corresponding marginal portions 30 of the opposite main trunk section, the inner back wall of one of said main trunk sections being movable with respect to the end walls of the same trunk section of which it forms a part, to position to form an opening in said main trunk section adapted to permit garments suspended in said main trunk section to hang down through said 35 opening when the main trunk sections are in opened wardrobe-forming position, foldable flaps of flexible water-proof material 40 connected with the opposite ends of said relatively movable inner back wall member and with the adjacent margins of the end walls of said main trunk section, said foldable flaps being adapted to form a water-proof connection between said inner back wall and said end walls, an inner telescoping member slidably mounted in said last-mentioned main trunk section, and movable to 45 and from extended position through said opening, an outer connecting back wall member mounted in position to overlap and inclose said relatively movable inner back wall member when the main trunk sections are 50 in trunk-closing position, said outer back wall member being movable to position to permit the opening and closing of said inner back wall member, means for detachably connecting said outer back wall member with each of said main trunk sections, 55 securing means located inside of the trunk and inaccessible from the outside of said trunk when the main trunk sections are in trunk closing position, said securing means 60 acting to prevent the releasing of said connection between the outer back wall member and either of said main trunk sections when the main trunk sections are in trunk closing position, and means for locking said trunk 65 sections in trunk-closing position.
6. In a trunk of the class described, the combination of a pair of opposite main trunk sections each having a front wall, end walls and an inner back wall portion the 70 margins of which are movable into and out of trunk-closing engagement with the adjacent corresponding margins of the opposite main trunk section, an outer connecting back wall member mounted in position to overlap and inclose said adjacent margins of 75 the inner back wall portions of said main trunk sections, detachable connecting means forming a detachable hinged connection between one of the margins of said outer back
- wall member and an adjacent main trunk section, said detachable connecting means comprising a connecting member adapted to be held nonremovably in connecting position when the main trunk sections are closed, 80 means for connecting said outer back wall member with the other main trunk section, and means for locking the main trunk sections in closed position.
7. In a trunk of the class described, the combination of a pair of opposing main trunk sections each having a front wall, end walls and an inner back wall portion the margins of which are movable toward and from the corresponding marginal portions 85 of the opposite main trunk section, the inner back wall of one of said main trunk sections being movable with respect to the end walls of the same trunk section of which it forms a part, to position to form an opening 90 in said main trunk section adapted to permit garments suspended in said main trunk section to hang down through said opening when the main trunk sections are in opened wardrobe-forming position, foldable flaps of flexible water-proof material connected with the opposite ends of said relatively movable inner back wall member and with the adjacent margins of the end walls of said main trunk section, said foldable flaps being adapted to form a water-proof connection between said inner back wall and said end walls, an inner telescoping member slidably mounted in said last-mentioned main trunk section, and movable to 95 and from extended position through said opening, an outer connecting back wall member mounted in position to overlap and inclose said relatively movable inner back wall member when the main trunk sections are 100 in trunk-closing position, said outer back wall member being movable to position to permit the opening and closing of said inner back wall member, means for detachably connecting said outer back wall member with each of said main trunk sections, 105 securing means located inside of the trunk and inaccessible from the outside of said trunk when the main trunk sections are in trunk closing position, said securing means 110 acting to prevent the releasing of said connection between the outer back wall member and either of said main trunk sections when the main trunk sections are in trunk closing position, and means for locking said trunk 115 sections in trunk-closing position.

Signed at Chicago, in the county of Cook and State of Illinois this 29th day of August, 1919.

WILHELMINE ANDERSON.
